UNITED STATES PATENT OFFICE.

JAMES F. LEE, JR., OF RIVER FOREST, ILLINOIS, ASSIGNEE TO THE PAPER MILLS COMPANY, OF CHICAGO, ILLINOIS, A CORPORATION OF ILLINOIS.

PACKAGE FOR STATIONERY.

Application filed June 11, 1925. Serial No. 36,334.

This invention relates to a new and improved package for stationery and more particularly, to a package containing a supporting shelf for a portion of the stationery.

5 In usual types of boxes for stationery the paper and envelopes are supported one upon the other which renders it necessary to remove one to reach the other. In some types of boxes the paper is carried beside the envelopes, but is unsupported so that when the paper is drawn out, it is difficult to replace it without wrinkling or damaging some of the sheets. Usual types of stationery boxes lack any separate means or receptacle for 10 holding pens, pencils or the like, which it is commonly desired to place in the box with the stationery and such pens or pencils often mark up the stationery and render some of it useless.

20 It is an object of the present invention to provide a new and improved stationery package including means for supporting the paper separate from the envelopes.

It is an additional object to provide such 25 a supporting means adapted to be drawn out from the body of the box with the paper and to support it when drawn out.

It is a further object to provide in such a 30 box a removable tray adapted to contain writers' articles.

It is still a further object to provide a box having a paper supporting shelf and article receiving box so formed and associated as to facilitate the withdrawal of the shelf.

35 Other and further objects will appear as the description proceeds.

I have illustrated a preferred form of my invention in the accompanying drawings, in which

40 Figure 1 is a perspective view of the package with the shelf and tray partly drawn out;

Figure 2 is a section taken on line 2—2 of Figure 1 and

45 Figure 3 is a section taken on line 3—3 of Figure 1.

The package comprises the box 11 having an open side through which the contents are inserted and removed. This side may be closed by any usual type of removable cover 50 which in itself forms no part of the present invention and has not been shown. The sliding tray 12 is fitted into the box and

this tray is provided with the downturned ends 13 fitted between the ends 14 of the box and the envelope housing members 15. The envelopes 16 are fitted in the housings 15 and the paper 17 rests upon the shelf 12. The sliding tray 18 is fitted into the box between the envelope housings 15. The upper side of the tray is open and the upper 60 edges of its side walls may bear against and aid in supporting the under side of the shelf 12. Both the shelf 12 and tray 18 are free to slide in the box and may be drawn out and inserted as desired. 65

As shown in Figure 3, the envelopes 16 are of less length than the depth of the box and the inner portion of the envelope housing members 15 may then be occupied by the filler members 19. The envelope housings 15 and filler members 19 may, if desired, be permanently secured together and to the box by gluing or by other securing means. The top of the box 11 is provided with the notch 20 and the front of the tray 18 is provided with the notch 21. These notches 20 and 21 are opposite each other, so that the paper 17 and shelf 12 may be readily grasped between the thumb and forefinger and drawn out of the box. It will be understood 70 that the package may be designed for varying sizes of paper and stationery and that the filler members 19 may or may not be desirable. Also, the envelope housings may be dispensed with in some cases and the tray 75 18 will then be positioned by the two lots of envelopes and in turn the tray will keep the envelopes in position.

The sliding shelf 12 may be drawn out when desired to remove sheets of paper and the remaining sheets may then be slid back into the box on the shelf without difficulty and without danger of wrinkling the paper. The tray 18 is adapted to contain pencils, pens, eraser or other writers' articles and to 80 keep them with the stationery with which they are to be used. 90

I have illustrated one preferred embodiment of my invention by way of example, but I contemplate such changes and modifications as come within the spirit and scope 100 of the accompanying claims.

I claim:

1. In a stationery package, a box having

an open side, a paper supporting shelf slid-
ably fitted in said box, said shelf comprising
a single piece of material having down-
turned ends serving as supports and enve-
lope housings fitted in the box and serving
with the box ends as guides for the shelf
supporting portions.

2. In a stationery package, a box having
an open side, a paper supporting shelf slid-

ably fitted in said box, said shelf having 10
downturned supporting sections, a pair of
spaced envelope housings fitted in the box
and serving with the box ends as guides for
the shelf supporting portions, and a tray
slidably fitted between the envelope housings. 15

Signed at Chicago, Illinois, this 29th day
of May, 1925.

JAMES F. LEE, JR
